VEHICLE IDENTIFICATION SIGN

Abraham Golub, 4881 22nd St. NW.,
Lauderhill, Fla. 33313

Filed Oct. 5, 1973, Ser. No. 404,073

Term of patent 14 years

Int. Cl. D20—03
U.S. Cl. D96—12 R

FIG. 1 is a perspective view of a vehicle identification sign showing my new design;

FIG. 2 is an end elevational view thereof on an enlarged scale;

FIG. 3 is an elevational view of the side opposite that shown in FIG. 1 on an enlarged scale;

FIG. 4 is a bottom view thereof on an enlarged scale; and

FIG. 5 is a fragmentary perspective view of a second embodiment of my new design.

The sign is fragmentarily shown in FIG. 5 for convenience of illustration, it being understood that the second embodiment differs from the first only in configuration of the top.

I claim:

The ornamental design for a vehicle identification sign, substantially as shown and described.
